FINIS BELLAMY, OF REDFORD, MICHIGAN

SAFETY DEVICE FOR STREET CARS

Application filed April 21, 1928. Serial No. 271,848.

My invention relates to safety devices for street-cars and has for its object to provide means whereby a street-car can be prevented from burning up when there is a short circuit which can only be cut out by removing the trolley from the trolley wire. Even though the current which drives the car is cut off, still the current from the control box will burn the car unless some means is quickly provided to release the trolley from the wire. As heretofore constructed, the motorman has no means of removing the trolley from the wire except to go to the rear of the car and pull down the trolley with a rope as is now the common practice. Frequently street-cars are crowded and under such circumstances it is difficult for the conductor to remove the trolley in time to prevent serious accident. Many serious accidents have resulted from the lack of proper equipment to cut off the current from the street-car when there is a short circuit. Another object of my invention is to provide means for automatically lowering the trolley-pole in the event the trolley runs off the wire. This arrangement will save the destruction of the wires and the trolley-pole in rounding curves and corners where the trolley not infrequently runs off the trolley-wire. The foregoing objects and others which will appear from the specification are accomplished by the means illustrated in the accompanying drawings, in which:

Fig. 1 is an elevation of a street-car with my device applied thereto.

Fig. 2 is an elevation of part of the rear of the car partly in section illustrated in detail the means by which the trolley is lowered from the trolley-wire either by the motorman or the conductor or automatically.

Fig. 3 is a section taken on line 3—3 of Fig. 2.

Fig. 4 is a section taken on line 4—4 of Fig. 2.

Fig. 5 is a section taken on line 5—5 of Fig. 2.

In the accompanying drawings reference numerals are employed to indicate the several parts.

1 is the body of a street-car. 2 is the control box. 3 is a trolley-pole. 4 is a trolley and 5 is a trolley-wire. In most instances in the construction of street-cars now employed the trolley-pole is pressed against the wire 5 by means of a spring 6 and keeps the trolley in contact with the wire to convey the electric current to the car. 7 is a rope connected to the trolley-pole by means of which the trolley-pole may be drawn down to disconnect the trolley from the wire. 8 is a weight of sufficient size and material to overcome the resistance of the spring 6. To this weight is connected a flexible wire rope 9 which normally is slack so as to permit the rise and fall of the trolley-pole 3 without affecting the weight 8. This weight is mounted in a cylindrical casing 10 which is connected to the roof 11 of the street-car and to the floor 12 in any suitable manner as by being mounted in a casing 13 secured to the floor by screws or bolts 14. This casing is bulged at 15 and apertured at 16 to permit the passage of the rope 17 therethrough. The rope 17 is secured to a spring 18 one end of which fits in a notch 19 to normally support the weight 8. The rope 17 passes to the front end of the car over a pulley 20 and carries on its end a ring 21 with which the motorman may pull the rope 17 to draw the spring 18 from the notch 19 which supports the weight and permits the weight to drop. The weight drops, drawing the pulley 4 away from the wire 5 and against the compression of the spring 6 which cushions the shock. This spring 18 may also be operated by the conductor of the car pulling on a rope 17 and thus the weight 8 may be actuated either from the front or rear of the car. When the motorman pulls on the ring 21 or the conductor pulls on the rope 17, the spring 18 passes from under the notch 19 on which the weight 8 rests, permitting the weight to drop by force of gravity and withdraw the pulley 4 from the wire 5 thus disconnecting the electric current from the car. I have also provided automatic means for dropping the trolley-pole beneath the wire,

which consists in a wire rope 22 connected to the trolley-pole in any suitable manner and leading over a pulley 23 which is connected to the body of the car in any suitable manner. This wire is also normally slack to permit movement of the trolley-pole in ordinary operation without affecting the rope 17 which is connected to the spring 18. In the event that the trolley 10 runs off the trolley-wire the trolley-pole will rise rapidly pulling on the rope 22 which in turn will pull the rope 17 and withdraw the spring 18 from the weight 8, permitting the weight 8 to automatically 15 drop and pull the trolley down below the trolley-wire. This is done so quickly that there is little opportunity for the trolley-pole to be bent and the wires destroyed. After the weight has dropped the trolley-pole it is then in a lower portion in the casing 10 and it is necessary to put it back in position. I have provided means for doing this which consists in a bore 24 in the weight 8 into which a rod or handle may be 20 inserted to lift up the weight above the spring 18 so that this spring will be again inserted beneath the notch 19 to hold it in its normal position. The casing 10 is slotted at 25 to permit the implement with 25 which the weight is to be lifted to slide in the slot. To prevent the weight from turning I have provided a boss 26 on the weight, which slides in the groove 27 in the casing 10.

From the foregoing it will be readily seen that if the street-car becomes short circuited and the current is flowing into the control box the motorman can immediately pull upon the rope 17 and withdraw the spring 18 from beneath the weight 8, whereupon the weight will immediately drop and disconnect the trolley-pole from the wire 5. Likewise, the motorman can pull upon this rope and withdraw the spring 18. The rope 17 is accessible from any part of the car except the rear platform.

Having fully described my invention and its mode of operation, what I claim is:—

1. In a device of the character described, a street-car, a trolley-wire, a trolley-pole for conveying a current of electricity to the car to drive the car, a trolley-pole actuating member positioned in one end of the car, means for connecting said member to the trolley pole, and means operable from either end of the car to release said actuating member to disconnect the trolley pole from the trolley wire.

2. In combination with a trolley car having an upwardly spring pressed trolley pole, a rope leading from said pole to within the car, a member attached to said rope and constantly tending to move downwardly so as to pull on said rope, a stop to prevent

downward movement of said member, and a cord within said car and connected to said stop in such a manner as to be adapted, when tensioned, to move said stop to permit said member to pull downwardly on said rope and to thereby pull down said trolley-pole against its spring. 70

3. In combination with a trolley car having an upwardly spring pressed trolley pole, a 75 rope leading from said pole to within the car, a member attached to said rope and constantly tending to move downwardly so as to pull on said rope, a stop to prevent downward movement of said member, and a cord within said car and connected to said stop in such a manner as to be adapted, when tensioned, to move said stop to permit said member to pull downwardly on said rope and to thereby pull down said trolley pole against its spring, 80 said cord extending longitudinally of the car so as to be accessible at a number of spaced points therein.

4. In combination with a trolley car having an upwardly spring pressed trolley pole, a 90 rope leading from said pole to within the car, a member attached to said rope and constantly tending to move downwardly so as to pull on said rope, a stop to prevent downward movement of said member, and a cord within said car and connected to said stop in such a manner as to be adapted, when tensioned, to move said stop to permit said member to pull downwardly on said rope and to thereby pull down said 95 trolley pole against its spring, said member comprising a weight sufficient to overcome the force of the trolley spring. 100

5. In combination with a trolley car having an upwardly spring pressed trolley pole, 105 a rope leading from said pole to within the car, a member attached to said rope and constantly tending to move downwardly so as to pull on said rope, a stop to prevent downward movement of said member, and a 110 cord within said car and connected to said stop in such a manner as to be adapted, when tensioned, to move said stop to permit said member to pull downwardly on said rope and to thereby pull down said 115 trolley pole against its spring, said cord extending longitudinally of the car so as to be accessible at a number of spaced points therein, said member comprising a weight, 120 said member comprising a weight sufficient to overcome the force of the trolley spring.

6. In combination with a trolley car having an upwardly spring pressed trolley pole, a rope leading from said pole to within the car, a member attached to said rope and constantly tending to move downwardly so as to pull on said rope, a stop to prevent downward movement of said member, and a cord within said car and connected to said stop 125

in such a manner as to be adapted, when tensioned, to move said stop to permit said member to pull downwardly on said rope and to thereby pull down said trolley against its spring, and a second rope connecting said pole to said cord, and of such a length as to be adapted when tensioned by extraordinary upward movement of said pole, to exert a pull on said cord to move said stop, as aforesaid.

10 7. In combination with a trolley car having a trolley pole, a trolley pole actuating member positioned in the car, means connecting said member to the pole, and means operable from a number of spaced points 15 within the car and operable to release said actuating member thereby permitting it to disconnect the pole from the trolley wire.

Signed at the city of Detroit, county of Wayne, State of Michigan, this 4th day of 20 April, 1928.
